(57) **CLAIM**

The ornamental design for a cart, as shown and described.

DESCRIPTION

FIG. 1 is a front isometric view of my new design for a cart
with the cover trays in place.

FIG. 2 is a side elevation view of the right and left sides,
which are mirror images, of FIG. 1.

FIG. 3 is a front side elevation view of FIG. 1.

FIG. 4 is a back side elevation view of FIG. 1.

FIG. 5 is a top plan view of FIG. 1.

FIG. 6 is a bottom plan view of FIG. 1.

FIG. 7 is a side elevation view of the right and left sides,
which are mirror images, of the embodiment of FIG. 1 with
the only difference being the top shelf is in an upright
position, it being understood that all other surfaces are the
same as the other views of this embodiment.

FIG. 8 is a side elevation view of the right and left sides,
which are mirror images, of the embodiment of FIG. 1 with
the only difference being the middle shelf is in an upright
position, it being understood that all other surfaces are the
same as the other views of this embodiment.

FIG. 9 is a side elevation view of the right and left sides,
which are mirror images, of the embodiment of FIG. 1 with
the only difference being the top and the middle shelf are in
an upright position, it being understood that all other surfaces
are the same as the other views of this embodiment.

FIG. 10 is a side elevation view of the right and left sides,
which are mirror images, of the embodiment of FIG. 1 with
the only difference being shelves are in the nesting position,
it being understood that all other surfaces are the same as the
other views of this embodiment.

FIG. 11 is a front isometric view of the embodiment of FIG.
1 with the only difference being cover trays are exploded up,
it being understood that all other surfaces are the same as the
other views of this embodiment.

FIG. 12 is a front isometric view of the embodiment of FIG.
1 with the only difference being cover trays are removed, it
being understood that all other surfaces are the same as the
other views of this embodiment.

FIG. 13 is a side elevation view of the right and left sides,
which are mirror images, of FIG. 12.

FIG. 14 is a front side elevation view of FIG. 12.

FIG. 15 is a back side elevation view of FIG. 12.

FIG. 16 is a top plan view of FIG. 12.

FIG. 17 is a bottom plan view of FIG. 12.

FIG. 18 is a side elevation view of the right and left sides,
which are mirror images, of the embodiment of FIG. 12 with
the only difference being the top shelf is in an upright
